UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAFT-RIGGING FOR RAILWAY-CARS.

1,288,659.

Specification of Letters Patent. Patented Dec. 24, 1918.

Application filed April 14, 1916. Serial No. 91,208.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is to provide a draft rigging of high capacity and simple construction.

In the drawings forming a part of this specification, Figure 1 is a horizontal sectional view, partly in top plan, of a draft rigging embodying my invention. In this figure the compression resisting springs are in twin arrangement. Fig. 2 is a cross sectional view taken on line 2-2 of Fig. 1. Fig. 3 is a perspective view of a modified form of yoke. And Fig. 4 is a cross sectional view of said yoke and adjacent parts of the draft rigging mounted between draft sills. Fig. 5 illustrates in cross section a further modification showing the springs in a quadruple arrangement. Fig. 6 is a perspective view of a follower adapted to be employed with the modified form of structure shown in Fig. 5. Fig. 7 illustrates a modification in which the springs are in twin tandem arrangement. Fig. 8 is a cross sectional view taken on the line 8-8 of Fig. 7. Fig. 9 is a perspective view of a follower adapted to be used with the modification illustrated in Figs. 7 and 8.

Referring to the drawings, I will first describe my invention as illustrated in Figs. 1 and 2. The numerals 10-10 designate draft members or parts of the car frame to which the draft rigging is applied, 11-11 front stop members, 12-12 rear stop members, all suitably secured to the draft members, 13 the draw-bar, only the rear portion thereof being shown in the drawing, and 14 a tie plate secured by suitable means, preferably the bolts 15-15 to the draft members and adapted to support the draft gear 16. The draft gear 16 comprises the front followers 17-17 and the rear followers 18-18, with compression resisting members as the springs 19-19 mounted between them. The draft

gear 16 is connected to the draw-bar 13 by means of a yoke 20, the said yoke is provided at its forward end with a transverse plate 21 to which are secured forwardly extended preferably integral spaced apart 60 arms 22-22 suitably perforated as at 23 for the passage of the coupler key 24 which secures the draw-bar between the two arms 22-22. Rearwardly extended from the plate 21 is the leg 25 of the yoke which in 65 preferable construction is near the bottom curved outwardly on either side as at 26-26 in Fig. 2 to conform to the adjacent springs 19. At its rear end the leg 25 is provided with the transverse plate 27 which is preferably integral, the same in preferable construction having the strengthening ribs 70 28-28 thereon. The front followers 17-17 are arranged one on either side of the leg 25 of the yoke. Each follower comprises the 75 transverse plate 29 against the inner face of which a spring is seated and a longitudinal preferably integral plate 30, the outer face 31 of which engages the inner face of the adjacent draft member 10 and is adapted to 80 slide thereon. The member 30 of each follower is on its inner face 32 conformed in shape to the adjacent spring 19. The rear followers 18-18 are arranged one on either side of the leg 25 of the yoke, each being the 85 counterpart of the front follower upon the same side of the leg of the yoke and requiring no further description. The axis of each of the springs 19 is indicated by the dotted lines 33 in Fig. 1 of the drawings, and it 90 will be observed that the plate 21 at the forward end of the leg of the yoke and the plate 27 at the rear end of said leg each extends laterally toward the draft members to points beyond the axes of said springs. The 95 front followers 17 and rear followers 18 are sufficiently spaced apart as indicated at the numerals 34-34 in Fig. 1 to permit the compression of the springs until the front set of followers come into engagement with the 100 rear set of followers, such engagement serving to limit the compression of the springs and to prevent their setting.

From the foregoing description the operation of the draft rigging will be understood, it being clear that on rearward movement of the draw-bar the transverse member 21 of the yoke 20 forces the front followers rearwardly, the sides of the followers sliding against the adjacent inner faces 110

of the draft members, the springs resisting their rearward movement until the front followers come into engagement with the rear followers. Meanwhile the yoke 20 5 slides rearwardly upon the tie plate 14 and the rear followers are held against movement by the rear stop members 12. On forward movement of the draw-bar the front followers are held in stationary position by 10 the front stop members, the yoke draws the rear followers forwardly thereby compressing the springs until the rear followers engage against the front followers. It will be observed that the four followers are identical in shape and interchangeable. For instance: a left hand follower may be converted into a right hand follower by turning the same upside down, the same follower can be converted into a right hand rear follower by turning it other end about and the same follower can be converted into a left hand rear follower by turning it other end about and upside down. Thus replacement of parts is easy, and only a small stock need 25 be carried. The split front and rear followers, that is, with the leg of the yoke passing between right and left hand followers permits the ready adjustability and full efficiency of the gear on lateral movement of the drawbar as when a train is operating upon a curved track. It is also evident that the draft gear is very compact and can be mounted and dismounted readily and can be used with draft members of a minimum vertical height.

In Figs. 3 and 4 a modified form of yoke is shown the yoke being designated by the numeral 40. At its forward end it is provided with the transverse plate 41 having 40 the perforated spaced apart forwardly extending preferably integral arms 42—42 between which the drawbar is received, a rearwardly extending leg 43 provided at its rear end with a transverse plate 44 the front and 45 rear transverse plates of the yoke being adapted to engage front and rear sets of followers, each set having a follower on either side of the leg of the yoke, said leg being provided on either side with a concavity 45 conformed to the springs 46—46, the said leg being substantially X shaped in cross section as shown in Fig. 4, and being mounted as in the form of my invention illustrated in Figs. 1 and 2, between the 50 draft members 47—47, and being supported together with the draft gear by the tie plate 48, which is suitably secured to the draft members. In Figs. 5 and 6 a further modification is shown. In this modification 55 the draft gear may be either a quadruple spring gear or a quadruple tandem gear, that is, each set of compression resisting elements comprises four units as the springs 50, each set of four being mounted two on either side of the leg 51 of the yoke and one

above the other, the yoke leg being provided on either side with upper and lower concavities 52—52 to conform each to its adjacent spring, the whole being mounted as in the other forms illustrated by the drawings 70 between the draft members 53—53, the draft gearing being supported by the tie plate 54 and each follower comprising the transverse plate 55 and the longitudinal plate 56, preferably integral therewith, each follower being of a sufficient height to permit the engagement of two springs 50, one above the other against the inner face 57 of one of the followers. In the modification illustrated in Figs. 7, 8 and 9, the numerals 80 60—60 indicate the draft members, 61—61 stop members which in the drawings are illustrated as side castings or cheek plates having the front stop shoulders 62—62, the front intermediate stop shoulders 63—63, 85 the rear intermediate stop shoulders 64—64 and the rear stop shoulders 65—65. The particular arrangement of parts illustrating this modification is that of a twin tandem gear. In this arrangement the yoke 66 is 90 provided with a leg 67 which has intermediate the front transverse plate 68 and the rear transverse plate 69, a central preferably block like stop 70 adapted to compress the rear gear 71 on rearward movement and 95 the front gear 72 on forward movement. The yoke is provided with the spaced apart legs 73—73 at its forward end to receive the drawbar 74 which is secured thereto by the coupler key 75. The followers are eight in 100 number and are arranged in sets of two, each set comprising a follower upon either side of the leg of the yoke. The front set of followers is indicated by the numerals 76—76, the front intermediate set by the 105 numerals 77—77, the rear intermediate set by the numerals 78—78 and the rear set by the numerals 79—79. The followers illustrated in this modification, as in all of those shown in the accompanying drawings are of 110 a general L shape, each having the transverse plate 80 against which a spring may be seated and the side plate 81 adapted to slide longitudinally upon the adjacent draft member. The eight followers are identical 115 in shape and each by turning to its suitable position can be used in any set of followers and on either side of the leg of the yoke. Between each front and front intermediate follower is mounted a compression resisting 120 member preferably an outer spring 83 and an inner spring 84 nested therein. The springs are seated at their ends against the followers and over-compression of the same is prevented through the engagement of an 125 end set of followers against an intermediate set of followers, the spaces shown at the numerals 85—85 between front and rear sets of followers of each gear being suitable to permit the compression of the springs to 130

a point short of their permanent set. The front and rear gears are each supported by means of tie plates 87-87 which are suitably secured to the draft members as by the bolts 88. The yoke as most clearly shown in Fig. 7 rides upon the tie plates. In forward movement of the drawbar the yoke is drawn forwardly, the rear intermediate followers being stopped by the rear intermediate stop shoulders 64, and the rear intermediate stop shoulders 64, and the rear transverse member of the yoke forces the rear followers 79 forwardly against the resistance of the rear set of springs until the rear followers engage the rear intermediate followers. Meanwhile the front followers are stopped by the front stop shoulders 62 and the front intermediate followers are drawn forwardly by the intermediate member 70 of the yoke, their forward movement being resisted by the front set of springs and stopped upon the engagement of the front intermediate followers against the front followers. The operation of the parts is similar on rearward movement of the drawbar. In this movement the front intermediate and rear followers being stopped by the front intermediate shoulders and the rear shoulders respectively while the spring resisted front followers are forced rearwardly by the transverse member 68 of the yoke and the rear intermediate followers are

forced rearwardly against the rear springs by the intermediate member 70 of the yoke.

I claim:

1. In a draft rigging, the combination with a yoke having a single leg extending rearwardly from the front end thereof, said leg having curved spring seats on each side thereof, of springs extending parallel with said yoke, and followers having also spring seats engaging the outer portions of the springs.

2. In a draft rigging, the combination with draft sills, stop-acting means, and a draw bar, of a yoke operatively connected to the draw bar, said yoke having a single longitudinally extending, centrally disposed leg, said leg having spring seats on each side thereof, a plurality of springs extending parallel with the leg of said yoke and co-operable with said seats, and a follower at each end of each spring, each follower having a transversely extending portion, and a longitudinally extending wall overlapping the corresponding spring, the longitudinally extending walls of the followers co-operating with the spring seats of the yoke to maintain the springs in proper position.

In witness that I claim the foregoing I have hereunto subscribed my name this 28th day of March, 1916.

JOHN F. O'CONNOR.
